PACKING

Raymond O'Connor, New York, N. Y.

Application October 29, 1931, Serial No. 571,722

Renewed July 11, 1934

7 Claims. (Cl. 229—87)

My invention relates to an improvement in a packing more particularly adapted for cigarettes and the novelty consists in the adaptation and arrangement of parts as will be more fully hereinafter pointed out.

There have been many attempts to construct a cigarette packing that would permit easy access to the cigarettes within, without the necessity of destroying part of the original package; that would indicate the condition of the cigarettes without opening and protect the cigarettes for shipment and seal in the aroma and flavor of the tobacco in the cigarettes and which would serve equally well as the holder of the cigarettes for the consumer after the packing is opened.

My packing has for the first time solved these problems, furnishing a container for the cigarettes:

That enables one to take cigarettes from the packing instantly, in a very practical manner, without destroying or tearing off any part of the package, yet allows for the actual breaking of the Government seal;

That permits the packing to remain in its original condition until the last cigarette is removed—thus preserving the freshness of the contents and preventing the tobacco from dropping out of the cigarettes after the package is once opened;

That permits the visibility of the cigarettes while they are still sealed in their original packing.

Referring to the drawing Figure 1 is a perspective of my packing in the filled and sealed condition.

Figure 2 is the same as Figure 1 with the outer envelope unsealed at the open end of the inner wrapper.

Figure 3 is the same as Figure 2 with the inner wrapper containing the cigarettes pushed up out of the outer envelope to make the cigarettes readily accessible for removal and with the Government seal differently mounted.

Figure 4 is a modified form of the upper portion of my device, the lower portion being broken away for convenience in illustration and in which the upper edge of the inner wrapper is cut away.

Figure 5 is another modified form of the upper portion as in Figure 4 in which only one cut out in the upper edge of the inner wrapper is used.

Figure 6 is another modified form of the upper portion as in Figure 4 in which one end of the upper edge of the inner wrapper is cut away.

In the drawing 4 is an inner wrapper of the usual inner and outer paper members with tin

foil between or of any suitable construction to form a strong inner wrapper or container which is sealed at one end 5 in the usual manner. The opposite end 6 is open and has cut out or finger members 7 on the opposite sides of the same.

An outer envelope 8 formed of cellophane or some other suitable transparent material is adapted to fit over the inner wrapper 4 and is sealed at one end 9 adjacent to 5 of the inner wrapper 4 and is foldably sealed at the upper end 10 over the open end 6 of the inner wrapper 4 with a tab 11 formed thereby and extending beyond the edge 12 of said sealed end 10.

A Government tax stamp 13 is adapted to be stuck on the side of the outer envelope 8 over the top of the folded upper end 10 to one side of the tab 11 so that said tab 11 will be free to be taken hold of and pulled in order to open the package. As this is done the stamp will be torn apart in accordance with the requirements of the internal revenue law. (Figures 1 and 2).

The Government tax stamp 13 may (as shown in Figures 3 to 6 inclusive) be stuck on the side of the outer envelope 8 over the folded upper end 10 so as to come under the tab 11 and so be broken when the tab 11 is pulled up and the upper end 10 is unsealed.

My packing is adapted to be packed, shipped and sold in the complete form as shown in Figure 1. To open this the tab 11 is taken hold of and pulled up and the stamp 13 is broken as shown in Figure 2 and the rest of the sealed end 10 of the outer envelope 8 is lifted to the position shown in Figure 2. The inner wrapper 4 containing cigarettes 14 is then pushed up so that the cut outs 7 are available and the tightly packed inaccessible cigarettes 14 can then be taken hold of between the thumb and finger and drawn upwardly and only one or more removed as may be desired.

The inner wrapper 4 containing the balance of the cigarettes 14 may then be pushed back into the outer envelope 8 and the end 10 of the outer envelope 8 will return to its folded position as when sealed so that the packing is again completed and the cigarettes therein will be protected until further required for use.

In the modified form shown in Figure 4 the complete upper edge of the inner wrapper 4 is cut away forming edge 15 and exposing the upper end of the cigarettes so that they are immediately available for easy withdrawal upon opening the seal end 10 of the outer envelope 8 and sliding up the inner wrapper 4 and contents to the desired position in the outer envelope 8.

In the modified form shown in Figure 5 there

is only one finger cut out 16 in the end of the inner wrapper 4 whereby the cigarettes adjacent thereto may be easily withdrawn on opening the seal end 10 of the outer envelope 8 and sliding up the inner wrapper 4 and cigarettes contained therein in the outer envelope 8 to the desired position.

In the modified form shown in Figure 6 one end of the upper edge of the inner wrapper 4 is cut away at 17 so that the cigarettes in said cut away portion are readily accessible when the end 10 of the outer envelope 8 is opened and the inner wrapper 4 and cigarettes therein are pushed up to the desired position in the outer envelope 8.

15 I claim:

1. In a cigarette packing an inner wrapper containing cigarettes and being sealed at one end and being entirely open at the opposite end, finger cut outs on opposite sides of said open end and a transparent outer envelope encasing said inner wrapper and being adapted to be opened only at the end encasing the open end of the inner wrapper.

2. A cigarette packing comprising an inner wrapper containing cigarettes and being sealed at one end and having the opposite end open, finger cut outs on opposite sides of said open end, a transparent outer envelope encasing said inner wrapper and adapted to be opened at the inner wrapper open end.

3. In a cigarette packing an inner wrapper containing cigarettes and being sealed at one end and being entirely open at the opposite end, finger cut outs on opposite sides of said open end and a transparent outer envelope encasing said inner wrapper and being adapted to be opened only at the end encasing the open end of the

inner wrapper whereby the condition of the tobacco in the cigarettes can be observed without opening the packing.

4. A cigarette packing comprising an inner wrapper containing cigarettes and being sealed at one end and having the opposite end open, finger cut outs on opposite sides of said open end, a transparent outer envelope encasing said inner wrapper and adapted to be opened at the inner wrapper open end whereby upon opening only the outer envelope end adjacent to the inner wrapper open end access to the cigarettes is readily secured without destroying the packing.

5. A packing comprising an inner wrapper sealed at one end and having the opposite end entirely open, finger cut outs on opposite sides of said open end, a transparent outer envelope encasing said inner wrapper and being adapted to be opened at the end adjacent the complete open end of the inner wrapper.

6. A packing comprising an inner wrapper sealed at one end and having the opposite end entirely open, finger cut out on one side of said open end, a transparent outer envelope encasing said inner wrapper and being adapted to be opened at the end adjacent the complete open end of the inner wrapper.

7. A packing comprising an inner wrapper sealed at one end and having the opposite end completely open, a cut down end whereby the cigarettes extend beyond said inner wrapper at said open end, a transparent outer envelope encasing said inner wrapper and being adapted to be opened at the end adjacent the completely open end of the inner wrapper.

RAYMOND O'CONNOR.
